UNITED STATES PATENT OFFICE.

FREDERICK HEATH, OF TACOMA, WASHINGTON.

CORNER AND JAMB TILE.

1,403,953.

Specification of Letters Patent. Patented Jan. 17, 1922.

Application filed May 1, 1918. Serial No. 231,838.

To all whom it may concern:

Be it known that I, FREDERICK HEATH, a citizen of the United States, and a resident of Tacoma, in the county of Pierce and State of Washington, have made certain new and useful Improvements in Corner and Jamb Tiles, of which the following is a specification.

My present invention relates generally to building blocks, and more particularly to corner and jamb tiles, my object being the provision of a tile having especial advantages on account of its simplicity and many uses.

The corner and jamb block or tile provided by this invention consists of a composite group of elements each having a longitudinal void and the elements being defined by intermediate narrow slot like voids along which the block may be divided into its elements. The block formed is intended to be set with the voids running vertically, it is so proportioned as to close horizontal courses of hollow tile construction to complete wall corners and jambs, it is so arranged that in alternate courses, it may lie in angular or reverse position so that portions of the corner and jamb block overlap and bond into the wall, while completing an alignment of webs and shells with an element or elements of the corner and jamb block above and below. The thickness of the corner and jamb block is determined with relation to its length and to the wall blocks so that the running bond of the wall blocks in the horizontal courses is not disturbed, and the use of fillers at the corners and jambs, as is now common, is obviated.

In the manufacture and use of such hollow tile, it is essential that the block may be readily divided by a blow of the trowel or hammer to separate the block into its elements without destroying the ware or impairing the use of the separated parts in the wall. In the methods heretofore known of scoring and notching of blocks for the purpose of breaking them into sections, the following difficulties have been encountered. If sharp grooves are formed along the exterior of the blocks, these grooves result in the starting of cracks during the burning of the ware in the kilns and in the frequent warping and separation of the blocks, with a result that a very large percentage of the blocks is useless and this waste offers a prohibitory expense for the use of such

blocks as building material. If such scores be of smooth or rounded character, the exterior appearance of the block in the wall precludes using such a block for an outside finish. Furthermore, such scores are not effective in materially facilitating the breaking of the block.

It is an object of the present invention to provide such a block which may be manufactured by the effective method of continuous extrusion of a column of clay and which is divisible into its elements by reason of a narrow slot-like void between the elements so arranged and proportioned that the loss due to cracking resulting from heat treatment in the kilns is almost entirely eliminated. The block may be used as a whole without offering any weaknesses in the wall and may be handled both before and after burning without danger of breakage and may present the desired exterior appearance and yet be very readily divided by the use of a mason's trowel or hammer. The method and manner of accomplishing these objects is made apparent in the following description and the novel characteristics are summarized in the claims.

In the accompanying drawings illustrating my present invention:—

Figure 1 is a perspective view illustrating the use of my invention as a corner tile;

Figures 2 and 3 are plan views of the tile in alternate courses, one reverse with respect to the other.

Figure 4 is a detailed perspective view of my improved tile;

Figures 5 and 6 are sectional plans along opposite courses of the wall showing the tile used to form a recess for the reception of a window frame in an 8 inch wall.

Figures 7 and 8 are similar plans showing the use of the tile in connection with the formation of a window frame receiving recess in a 12 inch wall and,

Figure 9 is a sectional plan showing the whole tile set on the jamb side and forming and leaving a 4 inch recess for the frame.

Referring now to these figures, and particularly to detailed Figure 4, my invention proposes a tile generally indicated at 10, having five (5) voids 11, 12, 13, 14 and 15, of which the voids 11, 13 and 15 are in parallel spaced relation, and preferably square in cross section. The voids 12 and 14 occur between the voids 11, 13 and 15, void 12 being between the voids 11 and 13, and void

14 being between the voids 13 and 15, and these voids 12 and 14 differ materially in shape and extent from the remaining voids. Each of the voids 12 and 14 is relatively narrow, and extends at its opposite sides to points relatively close to the side faces of the tile, much closer in fact than the sides of the voids 11, 13 and 15.

To avoid the use of sharp grooves or notches in the inside or outside of the tile and yet to facilitate breaking as described, these voids 12 and 14 are very carefully proportioned with relation to the rest of the block. It will be noted that the width of these voids is approximately one half of the thickness of the walls of each element around the voids 11, 13 and 15. To avoid the sharp corners, the narrow voids are extended toward the outer sides of the block a distance approximately one half way through the normal wall of the block, leaving the bridging portion across the ends of the slot-like voids about one half of the thickness of the walls of the elements. These voids 12 and 14, it will be noted, are approximately rectangular and they may be formed as the clay is extruded from the die in a column, subsequently severed into the short lengths forming the complete blocks, thus facilitating rapid manufacture. The complete block presents no sharp edges or grooves of a character likely to start cracks during the heat treatment in the kilns. It will also be noted that the wall portion opposite these voids 12 and 14 affords a strip approximately equal to the width of the void along which it may be struck with the edge of the trowel or mason's hammer. Practice has demonstrated that this permits easy breaking of the block and yet the block when broken is very strong where strength is required. If such blocks have a narrow V groove either inside or outside the block it must be struck very accurately, and it thus requires considerable skill to successfully break blocks of the character heretofore made divisible by such methods.

From an inspection of Fig. 4 and other figures, it will be noted that the composite block forms a series of square tubular sections having walls of material thickness, the sections being defined intermediately by the voids 12 and 14. These voids 12 and 14 are preferably of a width corresponding to a normal vertical mortar joint so that when the blocks are placed in the position shown in Figs. 5 to 9 inclusive, the walls of the sections are in alignment with similar walls of corner or jamb blocks above or below and where a vertical mortar joint occurs in one course, it is in alignment with a void 12 or 14 in the course above or below.

As set end-wise in connection with the corner structure, the closed sides of the tile

so formed will obviously close longitudinally voids of hollow wall blocks, and by reversal in alternate courses the regular wall blocks will be overlapped so as to form a bonded and finished corner and obviate the necessity for odd lengths of wall blocks for fillers, as is now the common practice.

It is equally obvious that in alternate courses a full block 10 and a single section 16 thereof may be utilized to form recesses 75 receiving a window frame 17, as in Figures 5 and 6, in connection with a 5½ inch frame recess within an 8 inch wall.

It is equally obvious from an inspection of Figures 7 and 8, that a full block 10 and a single section 16 may be used in alternate courses with a 2 section tile portion 18, as in Figure 8, for forming a 6½ inch recess in a 12 inch wall.

It is equally obvious that the full tile may be used on the jamb side as indicated in Figure 9 to form a 4 inch recess for the reception of a frame 19.

It is of course to be understood that as set in the wall, two-thirds of the corner tile 90 will be bedded between the flat surfaces of the overlapping wall blocks, which form upper and lower beds of mortar on flat surfaces and insure strength, enabling jambs, piers and corners to be constructed as strong 95 as the body of the wall, and doing away with the commonly used end-to-end laying in like places.

I claim;—

1. A building tile consisting of a plurality 100 of hollow rectangular sections, the four walls of each section being substantially equal in thickness and there being a narrow rectangular void between adjacent sections extending for its full width on each side to a plane 105 materially nearer the adjacent outer side of the rectangular block than the adjacent inner surfaces of said sections, thus providing a weakened portion of such a width that the block may be readily severed by a blow of a 110 trowel or mason's hammer.

2. A corner and jamb tile consisting of a plurality of hollow square sections each having its four walls of substantially equal thickness, the adjacent walls of the sections being separated intermediately and joined at their outer edges, the joining being in the nature of integral connecting bridge members, the outer sides of which are flush with the outer surface of the blocks and the 120 inner sides of which are substantially parallel therewith, the transverse thickness of the bridge members being approximately one-half the thickness of the sides of the square sections, whereby a weakened portion is provided along which the block may be divided by a blow on the outer sides of such bridge 125 like connections.

FREDERICK HEATH.
